UNITED STATES PATENT OFFICE.

TIMOTHY J. SULLIVAN, OF NEW ORLEANS, LOUISIANA.

STAVE-FORMER.

SPECIFICATION forming part of Letters Patent No. 417,603, dated December 17, 1889.

Application filed July 2, 1888. Serial No. 278,755. (No model.)

To all whom it may concern:

Be it known that I, TIMOTHY J. SULLIVAN, of New Orleans, in the parish of Orleans and State of Louisiana, have invented certain new and useful Improvements in Stave-Formers; and I do hereby declare that the following is a full, clear, and exact description thereof, reference being had to the accompanying drawings, and to the letters of reference marked thereon, which form part of this specification.

My invention relates to stave-formers; and its objects are, first, to subject them to a uniform pressure; second, to adapt a series of staves to the invariable conformation of the formers; third, to bend the staves to a uniformly-varying contour, and, fourth, to attain these ends with structural simplicity and economy. I accomplish these aims by the device shown in the accompanying drawings, in which—

Figure 1 shows a side elevation of a stave-former operatively embodying the essential elements of my invention. Fig. 2 is an elevation of the clamp, showing the relative location of the inclosed stave. Fig. 3 is a plan view thereof. Fig. 4 indicates the clamp opened to receive the stave; and Fig. 5 represents a transverse section of the clamp, taken 30 on the line $y y$ of Fig. 3.

In the manufacture of barrels it is highly

desirable to have the blanks bent to a common contour, so that when located in the barrel a horizontal plane taken at any altitude will discover every portion of the surface concentric to and equidistant from the axis. 35

The former is composed of two parallel curved faces $D' E'$, terminally connected at one end by a hinge I' , being respectively provided with cross-bars $d e'$, between which the 40 blanks are placed for conformation. The ends are locked together by a clasp H' . The extensions G' serve to connect thereto the adjacent ends of contiguous formers by links or clips. 45

Having thus fully described my improvements, what I claim is—

The former herein shown and described, consisting of parallel curved faces disposed to each other so as to permit the intermediate 50 accommodation of the stave, the said faces being hinged to each other at one end and having a locking-clasp at the other and immediately provided with a series of cross-bars in common vertical planes. 55

In testimony that I claim the foregoing as my own I affix my signature in presence of two witnesses.

TIMOTHY J. SULLIVAN.
